AIR CONDITIONER

Albert D. Greene, Alpha, Ohio, assignor to Trupar Manufacturing Company, Dayton, Ohio, a corporation of Ohio

Application September 26, 1932, Serial No. 634,837

10 Claims. (Cl. 62—135)

This invention relates to new and useful improvements in air conditioners.

It is one of the principal objects of my invention to provide for easy attachment to the conventional ceiling fan, a simple, economical and efficient air conditioner.

In the floor or cabinet type of air conditioner, the conditioned air is blown out into the room to be cooled, but in my device air is taken in at the fan height for conditioning by an expansion coil below the fan, and then diffused downwardly by baffles to all parts of the room. These baffles also act as inclined channels to receive and conduct to a center reservoir below them, the water of condensation which drips from the expansion coil.

It is another object of my invention to provide the fan with a housing which firmly supports the expansion coil and baffles in spaced relation below the fan to promote a proper diffusion of the conditioned air and an efficient drainage of the water of condensation to the drip pan. The water conducted to this pan by the baffles is abstracted by an injector on the compressor.

Another object of the invention is to provide means for including a number of my ceiling fan air conditioners in multiple with a single compressor, whereby more than one room may be cooled from a single source of refrigerant supply.

Other important and incidental objects will be brought out in the following specification and particularly set forth in the subjoined claims.

In the accompanying drawings illustrating one form of embodiment of the invention, Figure 1 is a top plan view of my air conditioner. Figure 2 is a transverse sectional view taken through the same on the line 2—2 of Figure 1. Figure 3 is a sectional view taken on the line 3—3 of Figure 1, showing how the baffle plates overlap.

Figure 4 is a sectional view taken on the line 4—4 of Figure 1, showing the condensation drain reservoir and withdrawal tube, together with the liquid refrigerant inlet and gaseous refrigerant outlet tubes. And Figure 5 is a side elevational view of a conventional compressor for use with one or more of my ceiling fan air conditioners.

Referring to the accompanying drawings for a detailed description of the form of embodiment of my invention disclosed therein, the numeral 1 designates a vertical tubular support for the motor housing 2 of a conventional ceiling fan 3. For the purpose of utilizing this fan to condition the air in the room containing it, I have provided the following means.

Clamped to the fan motor housing 2 is a

split band 4 from which horizontal arms 5 radiate to an annular rim housing 6. At their outer ends these arms are bent downwardly to form vertical ports 7 which are secured by screws 8 to the interior surface of the rim. (See Figures 1 and 3).

Supported upon diametric rods 8^a that are secured at their ends to the rim housing 6 below the fan 3, is an expansion coil or evaporator 9 made up of a finned copper tube 10. Connected to the inner end of this tube is a thermostatic expansion valve 11 which is secured to one end of a liquid refrigerant inlet tube 12. The latter is brought into the housing 6 through the tubular support 1, from a water jacketed condenser coil 13 on a suitable compressor 14. The gaseous refrigerant is withdrawn from the expansion tube 10 by an outlet tube 15 connected to its outer end. This outlet tube 15 passes through the tubular support 1 to the compressor 14 which compresses the gaseous refrigerant and introduces it to the condenser 13 through the tube 12. (See Figure 5).

Secured at their inner ends to the rim housing 6, below the expansion coil 9, are radial baffles 16. Each baffle preferably consists of an elongated metal plate of substantially triangular shape, that is formed with oppositely turned flanges 17 and 18 along its longitudinal edges. As shown in Figures 3 and 4, the baffles are so inclined beneath the expansion coil that their flanges 17 overlap the flanges 18 of adjacent baffles without touching each other. When so arranged, these baffles receive the water of condensation abstracted from the surrounding air by the finned expansion coil above, and conduct it to a central drain reservoir 18^a which depends from their inner ends. This reservoir is formed with an axial hole 19 through which a cord 20 for operating the switch 21 of the fan motor 2 projects.

The radial baffles 16 by virtue of their construction and arrangement, will also divert the air conditioned by the fan and expansion coil, downwardly and outwardly to all parts of the room. This air is taken in at the fan height and circulated downwardly past the expansion coil which abstracts moisture from it, the water of condensation dripping upon the baffles which not only conduct it to the drain reservoir 18^a, but also direct the moisture-free air outwardly and downwardly between their spaced flanges 17 and 18. By these baffle means the conditioned air is diffused to all parts of the room from whose ceiling the fan depends.

The water of condensation which drains into the reservoir 18 from the baffles is drawn, by suction, into a tube 22 by a conventional injector 23 attached to the discharge line 24 of the condenser 5 water jacket 13 that surrounds the refrigerant tube 12 connected to the compressor 14. The water drawn into the tube 22 by the injector, is discharged from the latter through a drain pipe 25. (See Figure 5.)

10 In operation, the compressor is started to introduce a suitable liquid refrigerant such as methyl-chloride to the expansion coil 9 or evaporator. By pulling the switch cord 20 the fan 3 is started, whereupon its rotation will cause the air at the 15 height of the fan to be forced by the latter downwardly past the finned expansion coil 9 which will abstract heat and moisture from it. The air thus conditioned will be diffused downwardly and outwardly to all parts of the room by the baffles, 20 while the water of condensation at the same time flows along them into the drain reservoir 18.

The air conditioning device which I have just described may be connected in multiple with a single compressor if desired, so that one source 25 of refrigerant supply may serve all of them.

I do not desire to be limited to the details of construction and arrangement herein shown and described, and any changes or modifications may be made therein within the scope of the subjoined 30 claims.

Having described my invention, I claim:

1. In a device of the type described, a refrigerant evaporator, a housing concentrically surrounding the latter, a fan rotatable in said housing above the evaporator, and baffle means secured within the housing, below the evaporator, to drain the water of condensation from the evaporator and diffuse the conditioned air downwardly and outwardly.

40 2. In a device of the type described, a refrigerant evaporator, a rim housing concentrically surrounding the latter, a fan horizontally rotatable in said housing above the evaporator, and radial baffle means secured in the housing below the evaporator, and overlapping each other in spaced relation along their longitudinal edges to drain the water of condensation from the evaporator and diffuse the conditioned air downwardly and outwardly.

45 3. In a device of the type described, a refrigerant evaporator, a rim housing concentrically surrounding the latter, a fan horizontally rotatable in said housing above the evaporator, radial baffle means secured within the housing below the evaporator to diffuse the conditioned air downwardly and outwardly, and a drain reservoir at the inner ends of the baffles to receive from them the water of condensation.

50 4. In a device of the type described, a refrigerant evaporator, a rim housing concentrically surrounding the latter, a fan horizontally rotatable in said housing above the evaporator, flanged radial baffle members secured in the housing below the evaporator to diffuse the conditioned air downwardly and outwardly, and a drain reservoir secured to the inner ends of the baffle members to receive from them the water of condensation.

55 5. In a device of the type described, a refriger-

erant expansion coil, a rim housing concentrically surrounding the latter to support it, a fan horizontally rotatable in said housing above the coil, and baffle means secured within the housing below the coil to drain the water of condensation 5 from the coil and diffuse the conditioned air downwardly and outwardly.

6. In a device of the type described, a refrigerant expansion coil, a rim housing concentrically surrounding the latter to support it, a fan horizontally rotatable in said housing above the coil, radial baffle members below the coil, projecting inwardly from the rim housing, and a drain reservoir below the axis of the coil, the baffle members communicating with, and supporting, at 10 their inner ends, the said reservoir to conduct thereto the water of condensation which drips upon them from the coil.

7. In a device of the type described, a ceiling fan, a motor housing therefor, a vertical support 20 for said housing, a rim housing concentric with said motor housing, a split band applied to the latter, radial arms projecting from said band to the rim housing, to support the latter, an evaporator supported in said housing below the fan, 25 and radial air diverting and condensation-receiving members projecting inwardly, below the evaporator, from said rim housing.

8. In a device of the type described, a ceiling fan, a motor housing therefor, a vertical support 30 for said housing, a rim housing concentric with said motor housing, a split band applied to the latter, radial arms projecting from said band to the rim housing, to support the latter, diametric rods projecting between the rim housing below 35 the fan, a spiral expansion coil supported upon said rods, radial baffle members projecting inwardly from the housing, below the expansion coil, and a drain reservoir for the water of condensation, depending from the inner ends of the baffle members below the center of the expansion coil.

9. In a device of the type described, the combination with a compressor-condenser, of a ceiling fan, an evaporator located under said fan, 45 means below the evaporator for collecting the water of condensation from it, means for conducting a liquid refrigerant from the compressor-condenser to the evaporator, means for delivering cooling water to the condenser, and an injector on the compressor-condenser, operated by said cooling water for withdrawing the water of condensation from the evaporator.

50 10. In a device of the type described, the combination with a compressor-condenser, of a ceiling fan, an evaporator located under said fan, a drain reservoir under said evaporator, means for conducting a liquid refrigerant from the compressor-condenser to the evaporator, baffle means for receiving the water of condensation from the evaporator and conducting it to the reservoir, means for delivering cooling water to the condenser, and injector operated by said cooling water, and a tube connected between said injector and the drain reservoir whereby the water of condensation may be withdrawn from the latter by the injector.

ALBERT D. GREENE.
